SHOE FORM

William J. De Witt, Auburn, N. Y., assignor to
Shoe Form Co., Inc., Auburn, N. Y., a corpora-
tion of New York

Application December 17, 1932, Serial No. 647,781

17 Claims. (Cl. 12—128.5)

This invention relates to an improvement in a shoe form and more particularly to an expansible toe form provided with a prong adapted to engage the insole of the shoe in which the form is inserted and to prevent the form from working backwardly out of the position which it should occupy and in which it is set.

Toe forms of this general type are inserted in the toes of shoes and expanded therein to plump out the toe and thus simulate the appearance of the shoes when in use. There is however a tendency of the toe form to work back out of the position in which it has been placed so that the shoe no longer presents a pleasing appearance. 10 One way of counteracting this tendency is to equip the form with a prong which enters the upper surface of the insole and resists the outward movement of the form. Various types of forms so equipped are shown for example in my Patents 20 Nos. 1,632,955 granted June 21, 1927, 1,736,780 granted November 26, 1929, 1,774,702 granted September 2, 1930, 1,817,299 granted August 4, 1931 and 1,821,695 granted September 1, 1931.

The prongs with which the toe forms disclosed 25 in these patents penetrate the surface of the insole of the shoe by reason of their structure, inherent resiliency and mounting and their positions are determined by the portion of the forms to which they are secured or of which they are 30 parts.

The primary object of this invention is to provide a toe form having a prong which is yieldably held with its tip penetrating the surface of the insole of a shoe, into which the form is inserted, by means independent of the prong and not by reason alone of the inherent resiliency 35 of the prong.

A further object of this invention is to provide 40 a toe form having a cross brace by which it is expanded or contracted and a prong which will engage the cross brace and yieldably prevent the cross brace from shifting out of that position in which the toe form has been given the desired amount of expansion, such prong also being, if desired, capable of shifting the position of the cross brace.

A still further object of this invention is to provide 45 in the toe form a prong by which the form is held against shifting by reason not only of the entry of the tip of the prong into the insole but also of a yieldable frictional contact of another portion of the prong with the insole.

Another object of this invention is to provide a 50 form having a prong the tip of which penetrates the surface of the insole, the points of pene-

tration being variable so that the prong will not be visible to the casual observer and yet be readily accessible for disengagement when the form is to be removed from the shoe. This obviously is a desirable feature in view of the variance in height 5 of the vamps of shoes.

Other objects of this invention will appear from a consideration of the following description and of the accompanying drawing which forms a part thereof and in which:

Fig. 1 is a side elevation with parts broken away, 10 of a toe form, including one embodiment of this invention, located in a shoe in the toe expanding position;

Fig. 2 is a bottom plan view of the toe form 15 shown in Fig. 1;

Fig. 3 is an enlarged sectional view taken along the lines 3—3 of Fig. 2; and

Fig. 4 is a view similar to Fig. 1 in which the toe form includes another embodiment of this 20 invention.

The toe form 10 shown in the drawing comprises ball flanges 11 connected in the well known manner by a cross brace 12. The cross brace 12 is pivotally secured at one end to a flange 11 25 by a button 15. A button 16 fixed to the other end of the cross brace is adapted to travel in an arcuate slot 17 formed in the other flange 11. Suitable bosses 18 or other positioning means may be provided to determine the position of 30 the cross brace. It will be understood that by the pivotal movement of the cross brace the side walls of the form 10 may be separated or brought toward each other and the form thus expanded or contracted. The form after being inserted 35 into the toe of a shoe 20 as shown in Figs. 1 and 4 is expanded to plump out the toe of the shoe and is contracted to facilitate its withdrawal from or its insertion into the shoe.

Pivoted upon the button 15 is a prong 21 having 40 a substantially right angled corner 22 intermediate its ends and terminating in a sharpened tip 23 which will enter the surface of the insole 24 and prevent the unwanted backward movement of the toe form 10 out of the shoe 20. 45 In both embodiments shown the prong 21 engages the cross brace 12 and yieldably holds it in the position in which it was set. These embodiments differ in the contour of cross brace engaging portion of the prong and will now be 50 separately described.

In the embodiment shown in Figs. 1 and 2 the portion 25 of the prong between the corner 22 and the tip 23 is provided with a plurality of loops 26 into any selected one of which the cross 55

brace 12 enters. The bases of the loops 26 bear upon the insole 24 and are yieldably held in such frictional contact by the cross brace 12.

Since there are a plurality of loops 26 the position of the tip in this embodiment is not determined by the location of the cross brace alone but is also determined by the loop which the cross brace enters. Thus the position of the tip may be varied so that with a shoe having a low vamp it may be set further in the toe of the shoe than with a shoe having a high vamp.

In the embodiment shown in Fig. 4 the portion 30 of the prong is provided with a loop 31 which receives the cross brace 12 and also with a second loop 32 the base of which rests upon the insole of the shoe. The cross brace 12 thus yieldably holds the nut 32 in frictional contact with the insole and the tip 23 in the surface of the insole while the cross brace is held in position by the prong.

When a form embodying this invention is to be inserted in a shoe the prong 21 is swung on the button 15 so that the tip 23 rests on one of the ball flanges and is out of contact with the insole. The form is then pushed by the use of a forming iron or other means firmly up into the toe of the shoe and the prong swung to remove the tip from the flange. The cross brace 12 is then shifted to expand the form and fill out the shoe the prong being moved into the toe by the brace. Thus any tendency of a toe form embodying this invention to move backward will be opposed by the prong 15 both through the engagement of the tip 23 with the surface of the insole and through the frictional engagement of the prong with the surface of the insole both functions being due to the yieldable action of the cross brace 12 on the prong. It will further be apparent that due to the engagement of the prong 15 with the cross brace 12, any inward pivotal movement of the prong on the button 16 will move the cross brace 12 and thus expand the walls of the toe form and increase the pressure of these walls against the toe portion of the shoe. In the first embodiment the loop which receives the cross brace is selected according to the height of the vamp of the shoe.

While two embodiments of the invention have been shown and described I am not limited thereto since other embodiments may be made without departing from the spirit and scope of the invention as set forth in the following claims.

I claim:

1. A toe form having a prong movably secured thereto, the tip of which is adapted to penetrate the surface of the insole of the shoe in which the form is inserted, and means carried by the toe form independent of the prong for engaging it and yieldably holding the tip thereof in contact with the insole whereby the withdrawal of the form from the shoe is opposed.

2. A toe form having a prong, the tip of which is adapted to penetrate the surface of the insole of the shoe in which the form is inserted, said prong having means spaced from the tip which means rest upon such surface and means independent of the prong for engaging it and yieldably holding the tip thereof and the means spaced from the tip in contact with the insole whereby the withdrawal of the form from the shoe is opposed.

3. A toe form having a prong, the tip of which is adapted to penetrate the surface of the insole of the shoe in which the form is inserted, and a cross brace, said cross brace and said prong being

independently carried by said form, the cross brace engaging the prong and yieldably holding the tip thereof in contact with the insole whereby the withdrawal of the form from the shoe is opposed.

4. A toe form having a prong, the tip of which is adapted to penetrate the surface of the insole of the shoe in which the form is inserted, said prong having means spaced from the tip which means rest upon such surface and a cross brace, said cross brace engaging the prong and yieldably holding the tip thereof and the means spaced from the tip in contact with the insole whereby the withdrawal of the form from the shoe is opposed.

5. A toe form having a prong, the tip of which is adapted to penetrate the surface of the insole of the shoe in which the form is inserted, said prong having means spaced from the tip which means rest upon such surface, and a cross brace, said cross brace engaging the prong in the space between the tip and the means and yieldably holding the tip and means in contact with the insole whereby the withdrawal of the form from the shoe is opposed.

6. A toe form having a prong, the tip of which is adapted to penetrate the surface of the insole of the shoe in which the form is inserted, and means yieldably engaging a portion of the prong to hold such portion upon the surface and cause it to coact with the tip to oppose the withdrawal of the form from the shoe.

7. A toe form having a movable cross brace connecting the side walls thereof and a prong, the tip of which is adapted to penetrate the surface of the insole of the shoe in which the form is inserted, said prong having a loop in which the cross brace enters whereby the cross brace is held in position by the prong.

8. A toe form having a cross brace connecting the side walls thereof and a prong, the tip of which is adapted to penetrate the surface of the insole of the shoe in which the form is inserted, said prong having a plurality of loops into any one of which the cross brace may enter and be held thereby in position, the bases of certain of said loops resting upon the surface of the insole and being held in contact therewith by the cross brace.

9. A toe form having a cross brace connecting the side walls thereof and a prong, the tip of which is adapted to penetrate the surface of the insole of the shoe in which the form is inserted, said prong having a loop in which the cross brace may enter and be held thereby in position, and a loop the base of which rests upon the surface of the insole and is held in contact therewith by the cross brace.

10. A toe form having ball flanges, a cross brace connecting said flanges, a button by which one end of the cross brace is pivoted to one of said flanges, the other end of the cross brace being slidable over the other flange to expand or contract the toe form, and a prong pivoted by said button to the flange and terminating in a tip which penetrates the surface of the insole of the shoe into which the form is inserted, said prong being between said cross brace and said surface and its tip being yieldably held in contact with the surface by said cross brace.

11. A toe form having ball flanges, a cross brace connecting said flanges, a button by which one end of the cross brace is pivoted to one of said flanges, the other end of the cross brace being slidable over the other flange to expand or

contract the toe form, and a prong pivoted by said button to the flange and terminating in a tip which penetrates the surface of the insole of the shoe into which the form is inserted, said 5 prong having a substantially right angled corner intermediate the ends thereof, the portion between the corner and the tip being bent to form a loop which receives such cross brace, the prong being between said cross brace and said surface 10 and its tip being yieldably held in contact with the surface by said cross brace.

12. A toe form having ball flanges, a cross brace connecting said flanges, a button by which one end of the cross brace is pivoted to one of 15 said flanges, the other end of the cross brace being slidably over the other flange to expand or contract the toe form, and a prong pivoted by said button to the flange and terminating in a tip which penetrates the surface of the insole 20 of the shoe into which the form is inserted, said prong having a substantially right angled corner intermediate the ends thereof, the portion between the corner and the tip being bent to form loops, one of which loops receives such cross brace 25 and the base of another loop resting upon the surface of the insole, the prong being between said cross brace and said surface and its tip and that loop the base of which rests upon the surface of the insole being yieldably held in 30 contact with the surface by said cross brace.

13. A shoe form comprising a hollow toe part having its opposite side walls provided with bottom inturned flanges, adjusting means connecting said flanges adapted to adjust the width of the 35 form, and an arm pivotally connected to one

of said flanges and adapted to engage said adjusting means to hold the form in place in a shoe, said arm having a downwardly extending prong adapted to engage the insole of a shoe.

14. A toe form having a cross member and an independent member pivotally carried by said form extending from the front of said cross member under the same and then upwardly in back of said cross member to engage the same and having a tip adapted to engage the insole 10 of a shoe.

15. A toe form having a cross member and an independent member pivotally carried by said form extending from the front of said cross member under the same and then upwardly in back 15 of said cross member to engage the same and having a tip adapted to engage the insole of a shoe, one of said members being resilient whereby said tip is held yieldingly in contact with the insole of the shoe.

16. A toe form comprising a hollow toe part having its opposite side walls provided with bottom inturned flanges, a movable crossbrace connecting said flanges and adapted to adjust the width of the form, and a prong having a tip 20 yieldably held by said crossbrace in engagement with the insole of a shoe, whereby the withdrawal of the form from the shoe is opposed.

17. A toe form having a prong, the tip of which is adapted to penetrate the surface of 30 the insole of the shoe in which the form is inserted, and movable means carried by the form, which means yieldably hold the tip of the prong in such surface penetrating position.
